O. S. GOOCH.

WORK ABUTMENT OR STOP FOR WORK BENCHES.

APPLICATION FILED APR. 8, 1915.

1,170,970.

Patented Feb. 8, 1916.

UNITED STATES PATENT OFFICE.

OSWALD S. GOOCH, OF CEDARVILLE, CALIFORNIA.

WORK ABUTMENT OR STOP FOR WORK-BENCHES.

1,170,970.

Specification of Letters Patent.

Patented Feb. 8, 1916.

Application filed April 8, 1915. Serial No. 19,963.

To all whom it may concern:

Be it known that I, OSWALD S. Gooch, a citizen of the United States, residing at Cedarville, in the county of Modoc and 5 State of California, have invented a new and useful Work Abutment or Stop for Work-Benches; and I do hereby declare the following to be a full, clear, and exact description of the invention, such as will enable others skilled in the art to which it 10 appertains to make and use the same.

This invention relates to a new and useful work abutment or stop for carpenters' benches and the like, and an object of the 15 invention is to provide a simple and efficient and practical device of this nature, in which improved features of construction are involved.

In practical fields the details of construction may necessitate alterations, falling 20 within the scope of what is claimed.

The invention comprises further features and combination of parts, as hereinafter set forth, shown in the drawings and claimed.

25 In the drawings:—Figure 1 is a view in perspective showing the improved stop or abutment as applied to a carpenter's work bench, illustrating the abutment partially raised or projecting above the surface of 30 the bench. Fig. 2 is a longitudinal sectional view on line 2—2 of Fig. 1. Fig. 3 is a transverse sectional view on line 3—3 of Fig. 1. Fig. 4 is a perspective view of the abutment or stop casing detached from the bench. 35 Fig. 5 is a detail perspective of the abutment removed from its casing.

Referring more especially to the drawing, 1 designates the work bench top having an 40 opening 2, one of the longitudinal edges of which is aligned parallel with the length of the bench while the other edge extends at an angle to the length of the bench. The 45 walls 3 and 4 of said opening are provided with recesses 5, and 6 denotes a trough-shaped casing having one side 7 conforming to the wall 4 of the opening, while the other side 8 conforms to the other angularly extending wall 3 of said opening. The sides 7 and 8 of the casing 6 are provided with 50 laterally extending flanges 9 and 10 fitting the recesses 5, there being screws 11 to hold said flanges in the recesses. One of the end walls of the opening 2 is beveled as shown at 12, and the adjacent edges of the end portions 13 of the flanges 9 and 10 curve from each other and terminate short distances

from the end parts of the beveled wall 12 of the opening 2, as shown clearly in Fig. 1. The casing 6 is provided with an extension casing 14 protruding downwardly, and 60 which is rectangular in cross section. The wall 15 is provided with an opening 16 and the side walls 17 of the extension casing 14 are constructed with recesses 18 adjoining the opening 16, and these recesses 18 form 65 bearings for the shaft pin 19, which is provided with a pinion 20, a hand wheel 21 and two collars 22 and 23. The collar 22 engages one of the side walls 17 of the extension casing, and interposed between the collar 22 and the collar 23 is a coil spring 25, thereby holding the pinion 20 adjacent the inner face 26 of one of the sides 17 of the extension casing. This spring not only holds the pinion against the inner face, but also 75 in engagement with a lug 27, thereby preventing the shaft pin from being rotated, until the shaft pin is pulled in the direction of the arrow *a* against the action of said spring. When the shaft pin is pulled in 80 such direction it is free to be rotated, and by its rotation the pinion imparts vertical movement to the rack bar 27, which is guided by and mounted in the extension casing 14. The collar 23 is held upon the extremity of the shaft pin by the cotter key 28.

Forming an integral part of the upper end of the rack bar is a trough-shaped work abutment or stop 29, the side 30 of which is in parallelism with and fits against the 35 side 31 of the casing 6, whereas the side 32 of the stop or abutment is angularly disposed with relation to the bench and fits against the angularly disposed side of the casing 6. Each of the sides 30 and 32 adjacent one end is provided with a laterally extending flange 33 having a curved edge 34 fitting the curvature of each of the flanges 9 and 10. The rear portions of the flanges 33 are provided with teeth 35, which are engaged by the edge of a flat board or the like when planing or dressing the same. The rear parts of the sides 30 and 32 are curved or beveled downwardly or forwardly to correspond with and fit the wall 12 of the opening 2. The abutment or stop is constructed trough-shaped with one of its sides angularly disposed, so that a board or the like, when disposed upon one of its longitudinal edges, may be received therein, the angularly extending wall 32 preventing forward movement of the board.

When it is desired to move the rack vertically, so as to adjust the stop or abutment to the proper position above the surface of the work bench, the shaft pin is pulled outwardly in the direction of the arrow α , against the action of the spring, thereby disengaging the pinion from the lug on the inner face of one of the sides 17 of the extension casing, after which a partial revoluble or rotary movement is imparted to the shaft pin, which also imparts movement to the pinion, which in turn raises and lowers the rack bar to the requisite position. The opening 16 allows the pinions to pass into the extension casing when inserting the shaft pin.

The invention having been set forth, what is claimed as new and useful is:—

In combination with a work bench having an opening, a casing trough-shaped in cross section secured in said opening and provided with a downwardly protruding extension casing, a trough-shaped stop or abutment mounted in said first casing and having one side disposed at an angle to the opposite side, said second trough-shaped casing having a rack bar extending through the exten-

sion casing, the lower portion of the extension casing having recesses in its opposite side forming bearings, the rear wall of the extension casing having an opening adjoining said recesses, a shaft pin mounted in said bearings and provided with a pinion meshing with the rack bar to impart a vertical movement thereto when the shaft pin is rotated, the opening in the extension casing constituting means through which the pinion may be passed so that the shaft may be inserted through the pinion, a lug on the inner face of one of the sides of the extension casing to be engaged by the pinion to prevent its rotation, and a spring on the shaft pin and against the action of which the shaft pin may be shifted to disengage the pinion from the lug, whereby the rack and its second trough-shaped casing may be adjusted vertically.

In testimony whereof I have signed my name to this specification in the presence of two subscribing witnesses.

OSWALD S. GOOCH.
